(57) **ABSTRACT**

A new poinsettia plant particularly distinguished by rich, dark, deep red-colored bracts, is disclosed.

1 Drawing Sheet

1

Genus and species: *Euphorbia pulcherrima*.
Variety denomination: 'NPCW24408'.

BACKGROUND OF THE NEW PLANT

The present invention comprises a new and distinct variety of poinsettia, botanically known as *Euphorbia pulcherrima* and hereinafter referred to by the variety name 'NPCW24408'. 'NPCW24408' was identified in Nairobi, Kenya in December 2018 as a cross-pollination from female parent EP-2015-5025 (unpatented) and male parent NPCW19282 (U.S. Plant Pat. No. 32,726). A seedling was selected in October 2019 and named 'NPCW24408'.

In May 2020, 'NPCW24408' was first vegetatively propagated by apical cuttings in Stuttgart, Germany and was found to reproduce true to type in successive generations of asexual propagation via apical cuttings.

SUMMARY

The following are the most outstanding and distinguishing characteristics of this new variety when grown under normal horticultural practices in Stuttgart, Germany.

1. Rich dark red colored bracts.

DESCRIPTION OF THE PHOTOGRAPH

This new poinsettia plant is illustrated by the accompanying photograph which shows an overall view of the plant. The photograph is of a plant approximately fourteen-weeks-old, grown indoors in Stuttgart, Germany in December

2

2022. The colors shown are as true as can be reasonably obtained by conventional photographic procedures.

DESCRIPTION OF THE NEW VARIETY

5 The following detailed descriptions set forth the distinctive characteristics of 'NPCW24408'. The data which define these characteristics were collected from asexual reproductions carried out in Stuttgart, Germany. Data was collected 10 on eighteen-week-old plants grown indoors in Stuttgart, Germany under greenhouse conditions in November 2024. Color references are to The R.H.S. Colour Chart of The Royal Horticultural Society of London (R.H.S.), 5th edition (2007).

15 Classification:

Family.—Euphorbiaceae.

Species.—*Euphorbia pulcherrima*.

Common name.—Poinsettia.

Variety.—'NPCW24408'.

20 Parentage:

Female.—Poinsettia variety EP-2015-5025 (unpatented).

Male.—Poinsettia variety 'NPCW19282' (U.S. Plant Pat. No. 32,726).

25 Plant:

Form.—Triangular.

Growth habit.—Upright.

Height.—37.0 cm to 39.0 cm.

Width.—35.0 cm to 40.0 cm.

Average number of inflorescences per plant.—5.

5	Keeping quality.—Very good (4 out of 5 based on a scale of 0 to 5 shelf-life test).	Margin.—Entire.			
	Time to produce a cutting.—5 weeks.	Size.—Length: 7.0 cm to 11.0 cm. Width: 4.5 cm to 7.0 cm.			
	Flowering response time.—Approximately 56 days.	Texture (both upper and lower surfaces).—Smooth.			
5	Propagation type.—Apical cuttings.	Folding along the main vein.—Absent.			
	Rooting habit and root color.—Freely branching and white (RHS NN155C).	Twisting.—Absent.			
	Lateral branches:	Rugosity between the veins.—Medium.			
	Color.—RHS 143A.	Venation pattern.—Reticulate.			
10	Length.—22.0 cm to 26.0 cm.	Vein color.—Upper surface: RHS 59A. Lower surface: RHS 181A.			
	Internode length.—2.0 cm to 4.0 cm.	Bract color.—Upper surface: RHS 46A. Lower surface: RHS 47A.			
	Diameter.—0.5 to 0.8 cm.	Bract petiole.—Length: 0.5 cm to 2.5 cm. Diameter: 0.2 cm to 0.3 cm. Color: Upper (part) surface: RHS 59A. Lower (part) surface: RHS 181A. Texture: Smooth. Strength: Sturdy.			
15	Branching habit.—Freely branching.	Cyme:			
	Number of lateral branches per plant.—5 to 6.	Diameter.—1.0 cm to 2.0 cm.			
	Texture.—Smooth.	Cyathia number.—4 to 6 per inflorescence.			
	Strength.—Strong.	Deformation of glands of the cyathium.—Absent.			
20	Leaves:	Timing of opening of cyathia.—Beginning of December, first pollen appears in parallel to opening of the nectar cups, stigmas appear 2 weeks later.			
	Quantity.—5 to 6 per lateral branch.	Cyathium.—Shape: Ovate. Texture (inner and outer surfaces): Smooth. Diameter: 0.2 cm to 0.5 cm. Length: 0.3 cm to 0.6 cm. Color: RHS 143B.			
	Arrangement.—Alternate.	Peduncle.—Color: RHS 142B. Length: 0.2 cm. Diameter: 0.1 cm. Texture: Smooth. Strength: Medium.			
	Number of lobes on the leaf blade.—0 to 2.	Nectar cups.—Number: 1 per cyathium. Diameter: 0.1 cm. Length: 0.4 to 0.5 cm. Color: RHS 13B. Shape: Lip shaped. Texture (both inner and outer surfaces): Smooth.			
25	Lobation depth.—Shallow.	Reproductive organs:			
	Depth of the deepest sinus of the leaf blade.—0.5 cm.	Stamen quantity.—10 to 12 per cyathium.			
	Shape.—Ovate.	Stamen shape.—Ovate.			
	Apex.—Acute.	Filament length.—0.3 cm.			
	Base.—Obtuse.	Filament color.—RHS 39A.			
	Margin.—Entire.	Pollen quantity.—Moderate.			
	Length.—10.0 cm to 13.0 cm.	Pollen color.—RHS 6A.			
	Width.—7.0 cm to 9.0 cm.	Gynoecium.—Present. Pistil quantity per cyathium: 1. Pistil length: 0.2 cm. Stigma form: Divided in 2 parts. Stigma color: RHS 183A. Style length: 0.2 cm. Style color: RHS 183A. Ovary length: 0.05 cm. Ovary color: RHS 143C.			
30	Texture (both upper and lower surfaces).—Upper: Smooth. Lower: Slightly pubescent.	Fruit and seed set: None observed.			
	Vein color.—Upper surface: Transparent. Lower surface: RHS 139D.	Disease and insect resistance: No particular disease or insect resistance observed.			
	Variegation.—Absent.	50 COMPARISON WITH PARENTAL LINE AND KNOWN VARIETY			
	Venation pattern.—Reticulate.				
35	Color.—Mature foliage: Upper surface: RHS 139A. Lower surface: RHS 137B. Immature foliage: Upper surface: RHS 141A. Lower surface: RHS 139B.	‘NPCW24408’ is distinguished from its parents as described in Table 1:			
	Leaf petiole.—Length: 3.5 cm to 5.0 cm. Diameter: 0.2 cm to 0.3 cm. Color: Upper (part) surface: RHS 59A. Lower (part) surface: RHS 181A. Texture: Smooth. Strength: Strong.	55 TABLE 1			
40	Transitional leaves.—Amount: Sparse. Shape: Ovate. Length: 8.0 cm to 10.0 cm. Lobing: Weak. Width: 5.0 cm to 6.0 cm. Color: Upper surface: RHS 203C and RHS 46A, both colors spread throughout the leaf surface with more concentration of RHS 46A toward the bract margins. Lower surface: RHS 137B and RHS 46A, both colors spread throughout the leaf surface with more concentration of RHS 46A toward the bract margins.	Comparison with Parental Lines			
45	Inflorescence:				
	Type and habit.—Cluster of cyathia.	60	Trait or characteristic	Female parent 'EP-2025-5025'	Male Parent 'NPCW19282'
	Quantity per lateral branch.—1.	Bract color	Rich dark red	Pale red	Rich medium to dark red but lighter than 'NPCW24408'
	Position relative to foliar plane.—Above.				
	Lastingness of inflorescence on the plant.—6 to 8 weeks.				
	Natural flowering season.—November and December.				
	Diameter.—20.0 cm to 23.0 cm.				
	Height.—3.0 cm to 4.0 cm.				
	Fragrance.—Absent.				
50	Bracts:				
	Number of bracts per inflorescence.—6 to 7.				
	Shape.—Ovate.				
	Apex.—Acute.				
	Base.—Obtuse.				
65					

US PP37,221 P2

5

TABLE 1-continued

Comparison with Parental Lines			
Trait or characteristic	Female parent 'NPCW24408'	Male Parent 'EP-2025-5025'	
Bract shape	Medium elongated	Elongated	More rounded
Leaf size	Medium to large	Large	Small to medium

COMPARISON WITH SIMILAR VARIETY

'NPCW24408' is most similar to the commercial poinsettia plant named Grande Italia (patent status unknown). Differences between the two varieties are described in Table 2:

6

TABLE 2

	Trait or characteristic	'NPCW24408'	Commercial line: Grande Italia
5	Rugosity between veins	Moderate	Shallow
	Bract colour quality	Richer, deeper red color than Grande Italia	Duller red color than 'NPCW24408'
10	Bract orientation	More upright than Grande Italia	More horizontal than 'NPCW24408'

I claim:

15 1. A new and distinct cultivar of Poinsettia Plant Named 'NPCW24408' as shown and described herein.
